UNITED STATES PATENT OFFICE.

WILLIAM GLASGOW, OF CHICAGO, ILLINOIS.

SIGNAL-OPERATING DEVICE FOR TRAINS.

SPECIFICATION forming part of Letters Patent No. 399,193, dated March 5, 1889.

Application filed August 26, 1887. Serial No. 247,986. (No model.)

To all whom it may concern:

Be it known that I, WILLIAM GLASGOW, residing in Chicago, in the county of Cook and State of Illinois, United States of America, 5 have invented a new and useful Improvement in a Signal-Operating Device for Railway-Trains, of which the following is a specification.

This invention relates to that type of signals for railway-trains in which a cord extending through a train of cars to the locomotive-cab is employed to operate a mechanical signal-bell in such cab; and the present improvements have for their object, first, to provide an 10 improved sectional signal-operating device permanent in each car and capable of convenient and easy coupling to form a continuous communication to the locomotive-cab, and which in case of accidental or forcible separation will not draw through the car at an imminent risk of bodily injury to the passengers and breakage of the lamps or windows, as would be the case where the ordinary signal-cord is forcibly or accidentally parted; sec- 15 ond, to provide a simple and effective coupling for the adjoining ends of my improved sectional signal-cord, with parts capable of ready and easy coupling and uncoupling, and which can be forcibly parted without injury, 20 as in cases where the train "pulls apart." I attain such objects by the construction and arrangement of parts illustrated in the accompanying drawings, in which—

Figure 1 is a side view, partly sectionized, 35 of a portion of a train of cars, illustrating the application of my present invention; Fig. 2, a detail side view, partly sectionized, of my improved sectional signal-cord and one of its carrying drums or sheaves; Fig. 3, a perspective view of the same; Fig. 4, a sectional elevation of the coupling for the ends of my improved sectional signal-cord, illustrating the operating or coupling mechanism of the same; Fig. 5, an elevation of the cap-plate that covers and forms a bearing for the operating 40 parts of the coupling, and Fig. 6 an edge view of the coupling with the cap detached.

Similar letters of reference indicate like parts in the several views. 45 Referring to the drawings, A A represent carrier drums or sheaves arranged at each end of the car, secured either to the inner face

of the end walls, as shown, or outside under the hood, if desired. In the periphery of each of these drums are two deep grooves 55 formed by the flanges a a' a^2 , as shown in Figs. 2 and 3, and in these grooves is wound in opposite directions the section of cord B, which at its middle passes from one groove to the other through an orifice, a^3 , in the center 60 flange, a' , so that each end or half of the cord will be in its respective groove. At its point of passage through the orifice a^3 the cord B is fixedly secured to the wheel-rim by an attaching-bolt, a^4 . 65

The cord B may be continuous from the two sheaves at the opposite ends of a car. It is, however, preferred to make it in sections of wire cords B to wind upon the sheaves, with a central connecting cord-section, C, extending through the car and uniting the inner ends of the cord-sections B B together, as such an arrangement admits of the use of a thin metallic cord, as B, for winding upon the sheaves and a heavier 70 cord-section, C, through the car for pulling upon by the conductor. The cord-section C is secured to the ends of the cord-section B by a loop, c, as indicated in Figs. 1 and 2, and its length is such as to bring the couplings D, 80 that unite the cord-section of each car, in vertical line with the car-buffers, so that when the cars are coupled together the couplings will be between the hoods of the car. It is preferable to form the cord-sections C of 85 braided wire, so that there will be no possibility of stretching or loss of motion throughout the whole train.

With the improved arrangement of sectional pull-cord having permanent connection to the carrying-sheaves, as above described, upon pulling upon one end of the cord B the action of the same will be to unwind from its forward carrying-sheave until its point of attachment a^3 a' is in line with 90 the direction of the pull, after which no additional movement can be attained. At the same time a corresponding length of the forward end of the cord B will be wound upon the sheave, and in this manner the longitudinal 95 movement of the pull-cord will be effected through the different cars until the signal-bell in the locomotive-cab is reached. 100

The carrying sheaves or drums A are jour-

naled in a bracket-frame, E, screwed to the car end, as shown, and having guide-orifices $e\ e'$ in its base, and pendent arm E', to guide and support the cord-section B between the 5 flanges $a\ a'$, and a^2 of the sheaves. These guide-orifices correspond with the ordinary cord-bushings of a railway-car.

F is a locking-pin hung from the bracket-frame E by a chain and adapted to pass 10 through a hole, e^2 , in such frame and through one of a series of circularly-arranged holes, a^3 , in the flanges of the sheaves A to lock the same from turning. This locking of the sheave is employed only when such sheave 15 constitutes the last one on the train, the purpose being to take up and hold the slack in the rear portion of the pull-cord.

The coupling by which the sectional pull-cords of the different cars or coaches, as above 20 described, are united together consists of a head, D, one end of which is provided with a recess, d, to receive the knotted end of the cord B, the other end being forked, as shown, to form, in connection with the pivoted latch-bar G, a closed link or orifice for receiving 25 and holding a ring or companion coupling upon another section of cord B.

The latch-bar G, of a C shape, as shown, is pivoted at d' to one of the forks D' of the 30 head D, its longer arm, g, being adapted to engage a spring catch or dog, H, the engaging-face of which is notched to receive the end of the arm g and offer frictional resistance to the movement of said arm. The face h of the 35 notch, in the direction in which the latch-arm g moves in a forcible detachment of the coupling, as in the pulling apart of the train, is made abrupt, as shown, so as to offer sufficient resistance to such movement of the arm, 40 while the other face, h', of such notch is made on a gradual incline to admit of the ready movement of the latch-arm in that direction when a union of the coupling parts is made or unmade in the ordinary manner by hand, 45 the position of the latch-bar G being indicated in dotted lines in Fig. 4. The spring bar or dog H is guided in the head D by rivets passing through the elongated slots $h^2\ h^3$, and it is forced downward to its engagement with 50 the arm g of the latch-bar by a double-acting spring, h^3 .

Owing to the latch-bar G being pivoted near the line of strain on the coupling, it will require a heavy pull on the hooked point of 55 the latch-bar to overcome the comparatively light engagement of the latch-arm g with the spring-catch H and permit of the parting of the coupling parts.

Having thus fully described my said invention, what I claim as new, and desire to secure 60 by Letters Patent, is—

1. A train-signal-operating mechanism comprising a local permanent cord-section in each

car, a coupling for uniting such sections together between the cars, and a carrying-sheave 65 at each end of the car, around which the cord-section loops or winds and is fixedly attached, in manner substantially as herein described.

2. A train-signal-operating mechanism comprising a local permanent cord-section in each 70 car, an automatic pull-apart coupling, essentially as herein described, for uniting such sections together between the cars, and a carrying-sheave at each end of the car, around which the cord-section loops or winds and is 75 fixedly attached, in manner substantially as herein described.

3. The combination, with the sectional pull-cord of a train-signal-operating mechanism, of a carrying-sheave, A, at each end of the car, 80 having grooves formed by flanges $a\ a'\ a^2$, the cord-section B, fitted in said grooves and passing from one groove to another through orifice a^3 , the clamping-bolt a^4 , and supporting frame or bracket E for said sheave, essentially as herein described.

4. The combination, with a sectional pull-cord of a train-signal-operating mechanism, of a carrying-sheave, A, at each end of the car, having grooves formed by flanges $a\ a'\ a^2$, the 90 cord-section B, fitted in said grooves and secured to the sheave by a clamping-bolt, a^4 , the supporting frame or bracket E, having orifice e^2 , and pin F, adapted to pass through said frame-orifice and one of a series of orifices, a^3 , in the rim of the sheave to lock said sheave at any desired adjustment, essentially 95 as herein described.

5. A train-signal-operating mechanism comprising a local permanent cord-section in each 100 car, consisting of a central connecting-section, C, and end metallic sections, B, the outer ends of which are provided with couplings D, a carrying-sheave, A, at each end of the car, having receiving-grooves in its periphery, 105 cord-section B, fitted in said grooves, and the clamping-bolt a^4 , for permanently connecting the cord-section B at its middle to the sheave, essentially as herein described.

6. A train-signal-operating mechanism comprising a local independent cord-section permanently arranged in each car and an automatical pull-apart coupling for the adjacent ends of each pair of the same, consisting of a head, D, having a recess, d, for attachment to 110 the ends of the cord-section B and forked ends D', the C-shaped latch-bar G, pivoted at d' to one of the forks, and the spring dog or catch H, having a notched engaging-face to engage and hold in a yielding manner the 115 longer arm, g, of the latch-bar, essentially as herein described.
